UNITED STATES PATENT OFFICE.

GEORGE M. WELLS, OF BOSTON, MASSACHUSETTS, ASSIGNOR TO THE
SOLIDITY IRON LAST COMPANY, OF NEW YORK, N. Y.

JACK FOR LASTS.

SPECIFICATION forming part of Letters Patent No. 281,742, dated July 24, 1883.

Application filed December 18, 1882. (No model.)

To all whom it may concern:

Be it known that I, GEORGE M. WELLS, of Boston, in the county of Suffolk and State of Massachusetts, have invented a new and useful Improvement in Jacks for Lasts, of which the following is a specification, reference being had to the accompanying drawings, forming a part hereof, in which—

Figure 1 is a vertical central section of a portion of one form of jack with my improvement upon it. Fig. 2 is a front elevation of the parts shown in Fig. 1.

My invention consists in a yielding shoulder adapted to press the block of the last toward the body of the last, and arranged upon that part of the jack which supports the rear part of the last, so that when the last is in place on the jack the block will be held in place by the yielding shoulder.

In the drawings, A represents the upper part of a jack, too well known to require description, with a socket to receive the stem of a cast-metal last.

B is the stem of the last, b its body, and b' its block.

D is the yielding shoulder, shown in the drawings as a projection from a plate, d, which plate is pressed upward by a spiral spring, d'. When the last is in place on the jack, the block b' is forced toward the body b by the shoulder D, which is pressed upward by the tension of the spring d', and thus the shoulder

D not only holds the block b' in place, but, in case it is not "home" before the last is placed upon the jack, tends to force it home.

35

It is advisable in most cases to use a second spring, d', as shown in the drawings, especially where the last is of the character shown in the drawings, in order that the block may not be brought into rigid contact with the 40 plate d or the outer surface of the socket of the jack.

There are two classes of jacks now used for supporting lasts, in one of which the upper part of the jack is a socket to receive a stem 45 on the last, substantially as shown in the drawings, and in the other of which the upper part of the jack is a heel-pin to enter a socket in the last; but it will be clear that my improvement is equally applicable to both these forms 50 of jacks, as it relates to the yielding shoulder D, acting to support the block and hold it in proper relation with the body of the last after the last is jacked, and not to the specific construction of the jack.

55

What I claim as my invention is—

In a jack for lasts, the yielding shoulder D, adapted to force the block b' against the body b when the last is jacked, all substantially as described.

GEO. M. WELLS.
